PRESSURE-CONTROLLED VALVE.

1,145,043.

Specification of Letters Patent.

Patented July 6, 1915.

Application filed June 14, 1912. Serial No. 703,644.

To all whom it may concern:

Be it known that we, WILLIAM F. TREIBER, a citizen of the United States, residing at Corning, in the county of Steuben and State of New York, and EMERY L. BULKLEY, a citizen of the United States, residing at Painted Post, in the county of Steuben and State of New York, have invented certain new and useful Improvements in Pressure-Controlled Valves, of which the following is a specification.

This invention relates to pressure controlled valves, and more particularly to valves of this type which are designed to operate at a predetermined pressure in a compressor receiver or like fluid receptacle to admit fluid pressure to a fluid actuated regulating means, and to release this fluid pressure when the pressure in the receiver or receptacle falls below a predetermined amount.

The object of the present invention is to produce a valve of simple construction which will operate quickly and positively when the desired pressure in the fluid receptacle is reached and will return with equal quickness and positiveness to its original position when the pressure falls below a desired amount.

The construction herein described and claimed can be used with any form of regulating mechanism wherein the regulating is by movement of a pressure actuated mechanism such as a piston, diaphragm or like device which is moved from normal position by pressure and returned thereto when the pressure is removed; for instance, the present valve may be used with various forms of pressure actuated discharge line or inlet regulating unloaders for compressors, for pressure actuated belt shifters and electric switches and like purposes.

For the purposes of description a practical embodiment of the valve is here shown, in connection with a compressor intake closing unloader.

In the drawings: Figure 1 shows a side elevation of a compressor and an inlet unloading valve controlled by a valve embodying our invention. Fig. 2 shows a vertical

inlet closing valve and the controlling valve. Fig. 3 is an elevation showing a detail of the controlling valve.

As shown the complete unloading mechanism comprises the unloader proper A and the controlling valve B.

The unloader proper consists of a casing 1 having an inlet pipe 2 and a discharge pipe 3 to the compressor. In the casing opposite the opening of the inlet pipe is a valve cylinder 4 in which moves a valve piston 5, to the head of which is secured a beveled valve disk 6.

In closing, this valve disk bears against a beveled valve seat 7 in the inlet opening. The back part of the cylinder communicates with the controlling valve B through a pipe 8 which leads to a valve chest 9 in which is positioned a cylindrical valve 10 provided with oppositely beveled valve surfaces 11 and 12 which are so placed as to position against beveled seats 13 and 14 in the valve chamber. From the valve seat 14 a pressure exhaust opening 15 leads to atmosphere. The valve is provided with a triangular shank 16 which is secured to a diaphragm 17 so placed across a closed bore in the casing as to divide it into two chambers 18 and 19. Air can pass freely from the chamber 18 to the nearer face of the valve on account of the shape of the valve shank. The chamber 18 is always open to receiver pressure through passage 20 and a pressure inlet pipe 21 which leads from a dirt and water collector of ordinary construction 22 connected to the discharge pipe 22^a of the compressor, or to the receiver (not shown). From chamber 19 a leak vent 23 leads to the atmosphere, its effective size being controlled by an adjustable needle valve 24. From this chamber a passage 25 leads through a nozzle 26 to a second closed bore in the casing which is likewise divided into two chambers 27 and 28 by a diaphragm 29 which may seat against the nozzle closing it. The chamber 27 is likewise connected with the dirt collector 22 by a pipe 30. Contacting with the diaphragm on the opposite side from the nozzle is a cup shaped plunger 31 which slides in a cylindrical bore 32 and 33.

is held against the diaphragm 29 by a spring 33 the tension of which can be adjusted by a screw 34. In order to give the plunger a sudden rather than a gradual motion when the pressure in chamber reaches a certain amount a friction plug 35 is provided which slides in a bore 36 in the casting and is held against the plunger by a spring 37. The tension of the spring 37 10 can be varied by the tension screw 38, and in this way the drop in pressure necessary to allow the valve 10 to return to its original position can be varied.

Leading from chamber 27 to chamber 19 15 is a leak passage 39 which contains a valve seat 40 against which seats a screw 41 forming a valve which can be opened to put the chambers in communication without the necessity of sufficient pressure to open the 20 valve formed by the diaphragm and the nozzle.

In operation when the pressure in the receiver reaches a point which is governed by the tension of springs 33 and 37 the diaphragm 29 will be forced away from the nozzle 26 allowing air at receiver pressure to pass through the nozzle 26. This pressure will be exerted on the diaphragm 17. The chamber 18 is also at receiver pressure 25 but the effective area of the diaphragm is smaller on this side and diaphragm 17 will be forced over. When diaphragm 17 is thus forced over, valve 10 is moved rapidly across its path of travel and closes exhaust opening 30 15, at the same time giving a free opening between chamber 18 and the valve chest 9, thus admitting air at receiver pressure to pipe 8. This will promptly force up piston 5 and valve disk 6 against valve seat 7, 40 completely closing inlet pipe 2 of the compressor and positively shutting off the intake without allowing any vibration or fluttering of valve disk 6, such as frequently occurs when the regulating valve allows pressure 45 sure to build up gradually instead of suddenly in cylinder 4. When the pressure in the receiver falls the diaphragm 29 will again close the nozzle, pressure in chamber will leak out through port 23 which is 50 always more or less open to the atmosphere, and the receiver pressure in chamber 18 will carry the valve 10 back to its original position closing off communication between the receiver and the unloader cylinder and opening 55 the unloader cylinder to atmospheric pressure through the exhaust opening 15. Due to the rapid action of valve 10 when returning to its original position, the movement of valve disk 6 when opening the intake will again be prompt and positive.

If it is desired to unload the compressor by hand, the valve in the passage 39 can be

opened allowing the valve 10 to be thrown at any pressure of the receiver.

It is to be understood that the present 65 showing and description discloses only one specified modification of our invention and other forms and modifications are included in the spirit and scope of the invention as expressed in the claims. 70

What we claim is:

1. A pressure controlled valve for use with fluid actuated regulating mechanism comprising a closed bore divided by a diaphragm into two chambers, adjustable means 75 for admitting fluid at a predetermined pressure to one of said chambers, a valve chest, a passage from said valve chest for connection with a regulating mechanism, a pressure exhaust opening in said valve chest, 80 a passage from said valve chest to said second chamber having an inlet opening in said valve chest, a valve adapted to control said inlet opening and said exhaust opening, said valve being attached to said diaphragm, and 85 a single inlet passage for admitting fluid under pressure to said second chamber and said inlet opening.

2. In a pressure controlled valve for use with fluid actuated regulating mechanism, a 90 valve chest, a passage from said valve chest for connection with a regulating mechanism, an exhaust opening in said valve chest, an inlet passage to said valve chest, a valve for controlling said exhaust opening and inlet 95 passage, a stem on said valve passing loosely through said inlet passage, an actuating diaphragm attached to said valve stem, a fluid admission passage for continuously admitting fluid to one side of said dia- 100 phragm and to said inlet passage, and means to admit fluid at a predetermined pressure to the opposite side of the diaphragm.

3. In a pressure controlled valve for use with fluid actuated regulating mechanism, 105 comprising a valve chest having a passage for connection with said regulating mechanism, said valve chest having also pressure inlet and exhaust openings therein, a valve in said valve chest for connecting said regulating mechanism with either said inlet or said exhaust opening, a motor for operating said valve, a valve for admitting fluid to said motor, a fluid motor for opening said valve at a predetermined fluid pressure, and 110 adjustable means for retarding the action of said motor.

4. In a pressure controlled valve for use with fluid actuated regulating mechanism, comprising a valve chest having a passage 115 for connection with said regulating mechanism, said valve chest having also pressure inlet and exhaust openings therein, a valve in said valve chest for connecting said regu-

lating mechanism with either said inlet or said exhaust opening, a motor for operating said valve, a valve for admitting fluid to said motor, a fluid motor for opening said valve at a predetermined fluid pressure, a resilient element for closing said valve, and a spring pressed plug frictionally engaging a surface of said resilient element to

retard the action of said second motor and said resilient element.
